WASHING MACHINE

Demetrios G. Alexopoulos, Milwaukee, Wis.

Application November 2, 1935, Serial No. 48,031

2 Claims. (Cl. 68—207)

This invention pertains to washing machines, and has primarily for its object to improve conventional structures by the provision of means to facilitate rinsing of the clothes without removal of the same from the washing receptacle.

Incidental to the foregoing, a more specific object resides in the provision of means for drawing off scum and dirt from the top of the washing water, and removing and storing the remaining

10 soap water for subsequent use, if desired.

A still further object is to provide a conventional wash tub or receptacle with an auxiliary reservoir for the storage of soap water, and a circulating pump communicating with the receptacle and reservoir, whereby withdrawal of scum is facilitated and the tub may be drained to either the auxiliary reservoir, or a suitable discharge to the sewer.

With the above and other objects in view, which 20 will appear as the description proceeds, the invention resides in the novel construction, combination, and arrangement of parts, substantially as hereinafter described and more particularly defined by the appended claims, it being understood that such changes in the precise embodiment of the herein disclosed invention may be made as come within the scope of the claims.

In the accompanying drawing is illustrated 30 one complete example of the physical embodiment of the present invention constructed according to the best mode so far devised for the practical application of the principles thereof.

In the drawing:

Figure 1 is a vertical section through a washing machine incorporating the features of the present invention.

Figures 2 and 3 are vertical sections through the upper valve controlling communication to the circulating pump, and illustrating the operative positions of the valve, and

40 Figures 4 and 5 are similar views of the lower valve for controlling discharge from the circulating pump.

Referring now more particularly to the accompanying drawing, the numeral 1 designates the main receptacle of a washing machine of any conventional type, the same being supported upon a frame 2, provided with the usual casters 3 for portability. Mounted on the frame 2 is an 45 electric motor 4, which through a conventional transmission 5 operates an oscillating agitator 6 mounted in the main receptacle, and also operates a wringer 7.

It is to be understood that the foregoing is 50 conventional, and therefore forms no part of the

present invention other than in the combination hereinafter claimed.

The receptacle 1 adjacent its upper end is provided with an auxiliary reservoir 8, which may be formed in any manner, but for the purpose of illustration the side wall of the receptacle 1 is turned inwardly at 9, and an outwardly flared annular rim 10 is welded or secured to the side wall in any suitable manner.

Below the juncture of the wall 9 and the rim 10, which form the reservoir 8, the rim 10 is bowed outwardly to form an annular channel 11 surrounding the main receptacle. Communicating with the channel are a plurality of openings 12, which are normally closed by the plates 13 15 slidably mounted in suitable brackets 14 secured to the inner face of the side wall of the main receptacle 1. Suitable hose or pipe connections 15 and 16 communicate with the main receptacle 1 to supply either hot or cold water from any 20 available source.

The receptacle 1 is provided with a drain outlet 17 communicating with a conventional type of pump 18, through the line 19, and disposed between the outlet 17 and the pump 18 is a three-way valve 20, which is connected with the annular channel 11 by a pipe 21. The discharge side of the pump is provided with a line 21, which may lead to a sewer, or any other source of disposal, and disposed in the line is a three-way valve 22, 30 communicating with the auxiliary reservoir 8 through the line 23. The pump 18 is operatively connected with the motor 4 by a belt 24.

Considering now the operation of the present invention, the main receptacle 1 is supplied with 35 either hot or cold water through the connections 15 and 16, the amount of water being gauged to the depth of the openings 12. After the washing operation is completed, the closures 13 are opened to permit the scum and dirt floating on 40 the surface of the water to enter the annular channel 11, and, to facilitate drawing off of the same, the valve 20 is set to the position illustrated in Figure 2, which creates a suction through the line 21' to the pump 18. At the 45 same time, the valve 22 is set in the position illustrated in Figure 5 of the drawing, which causes the scum and dirt to be discharged through the line 21.

After the scum is removed from the top of the 50 washing water, in some instances the operator desires to economize in the consumption of soap, and therefore provision is made for the drawing off of the soap water and storing the same in the auxiliary reservoir 8 for subsequent use, after 55

the rinsing operation is completed by introduction of either hot or cold water through the connections 15 and 16.

To drain the main receptacle 1 of soap water, and store the same in the auxiliary reservoir 8, the valve 20 is set in the position shown in Figure 3, while the valve 22 is turned to that position illustrated in Figure 4. After the soap water has been withdrawn from the main receptacle, and stored in the reservoir 8, when it is desired to subsequently use the same, the plug 25 is removed, permitting the soap water to drain back into the main receptacle. While it is not essential, it is preferable to provide a cover 26 for the main receptacle, and the auxiliary reservoir 8.

From the foregoing explanation, considered in connection with the accompanying drawing, it will be seen that an exceedingly simple, inexpensive, and efficient structure has been provided, in conjunction with conventional washing machines, which not only reduces the amount of labor required by the operator in rinsing clothes, due to the fact that they do not have to be removed from the main receptacle, but also makes provision for storage and subsequent use of the soap water, after the rinsing operation, thus effecting a material economy in the use of soap or other astringents.

I claim:—

1. A washing machine including a receptacle having an outlet opening in the side wall intermediate its top and bottom, and a drain opening in its bottom, means for regulating said outlet opening, a reservoir mounted upon said receptacle adjacent its upper end and provided with a drain opening communicating with said receptacle, a circulating pump having communication with the outlet and drain openings of said receptacle and also with the reservoir, and means controlling said communication for selectively withdrawing scum through said outlet opening or storing water from said receptacle in said reservoir. 5

2. A washing machine including a receptacle having a plurality of outlet openings in its side wall intermediate its top and bottom, and a drain opening in its bottom, means for regulating said outlet openings, a reservoir mounted upon said receptacle and provided with a drain opening 20 communicating with said receptacle, a circulating pump having communication with the openings in said receptacle and with said reservoir for withdrawing scum or dirt through said opening and storing water from said receptacle in said 25 reservoir, and valves for selective control of said pump communications.

DEMETRIOS G. ALEXOPOULOS.
